United States Patent Office

ROBERT FIDLER, OF TAUNTON, MASSACHUSETTS, ASSIGNOR TO HIMSELF AND THE
DIGHTON FURNACE COMPANY, OF DIGHTON, MASSACHUSETTS.

Letters Patent No. 66,231, dated July 2, 1867.

IMPROVED APPARATUS FOR FORMING SKELPS FOR SHEET-METAL TUBES.

The Schedule referred to in these Letters Patent and making part of the same.

TO ALL WHOM IT MAY CONCERN:

Be it known that I, ROBERT FIDLER, of Taunton, in the county of Bristol, and State of Massachusetts, have invented a new and useful improvement in Skelp-Tongs used in the Manufacture of Welded Wrought-iron Tubing; and I do hereby declare that the following is a full, clear, and exact description thereof, reference being had to the accompanying drawings, making a part of this specification, in which—

Figure 1 is a perspective view of the skelp-tongs with my improvement attached.

Figure 2, a view of one part of the dies; and

Figure 3, a direct front view of the machine.

My improvement may be applied to any style of skelp-tongs now in use. In those here represented, A is the lower jaw, permanently secured to some foundation. B, the upper jaw, hinged to the lower one at C, and operated through the lever D. On one end of these tongs is the die-holder or socket E, permanently affixed to the jaws either by rivets or screws, or cast in the same piece with them, and is divided into two parts, so that when the tongs are opened each jaw may carry with it its own part of the die-holder, and also whatever may be attached thereto. In this die-holder E are secured, by means of the bolts S S S S, the movable steel dies 1 2 3 4. To secure the die to the holder or socket the bolt S is passed through a hole drilled for it in the socket, and through the die at the slot F, when the nut is screwed down upon the bolt, holding the die in its place. The slot F permits the die to be moved to or from the centre. As the dies wear by use they may be filed or ground off upon those edges that strike or come in contact with each other at 5 6 7 8, and then regulated, by the set-screws I I I I and the bolts S, to the size required. The dies may be in two, four, or more parts, although it is found by use that four parts, as herein shown, is the preferable number.

What I claim, is—

The above-described improved apparatus for forming sheet-metal tubes.

ROBERT FIDLER.
